UNITED STATES PATENT OFFICE.

EDWARD F. ROGERS, OF GLOVERSVILLE, NEW YORK.

DESIGN FOR A GLOVE.

42,708.

Specification for Design.

Patented July 2, 1912.

Application filed January 2, 1912. Serial No. 669,105. Term of patent 7 years.

To all whom it may concern:

Be it known that I, EDWARD F. ROGERS, a citizen of the United States, residing at Gloversville, in the county of Fulton and State of New York, have invented a new, original, and ornamental Design for a Glove, of which the following is a specification, reference being had to the accompanying drawing, forming a part thereof.

The single figure of the drawing is a view

in perspective of a glove embodying my design.

I claim:

The ornamental design for a glove herein shown.

EDWARD F. ROGERS.

Witnesses:

FRANK C. WOOD,
GORDON P. YOUNG.
